UNITED STATES PATENT OFFICE.

ALFRED BRYANT DAY, OF KNOXVILLE, TENNESSEE.

WHEEL STRUCTURE.

1,109,905.

Specification of Letters Patent.

Patented Sept. 8, 1914.

Application filed August 14, 1913. Serial No. 784,805.

To all whom it may concern:

Be it known that I, ALFRED B. DAY, citizen of the United States, residing at Knoxville, in the county of Knox and State 5 of Tennessee, have invented certain new and useful Improvements in Wheel Structures, of which the following is a specification, reference being had therein to the accompanying drawing.

10 This invention relates to an improvement in wheel structures more particularly adapted for use in connection with mining cars wherein the axles are usually fixed to the car body and the wheel members rotate 15 on the ends of the axles.

The invention may be stated to be more specifically an improvement on the class of wheels illustrated and described in the patent to A. B. Day No. 907750 of December 20 29, 1908, and patent issued to Hugh W Sanford on July 2, 1912, No. 1031590.

The object of the present invention is to simplify the structures described in these above mentioned patents to produce a wheel 25 which will have a minimum number of parts; one wherein the use of fibrous packing or end washers are avoided between the hub and pedestal or body portion; one wherein a relatively thin lubricant may be 30 employed without escaping from the bearing; one which eliminates wear on the inner wheel hub and pedestal box, and one wherein in the roller members may be readily assembled in the hub part of the wheel and 35 there retained after the wheel has been removed from the axle.

A convenient embodiment of the invention is shown in the accompanying drawings, as well as a modified form thereof, but 40 it is to be understood that various changes can be made and employed in lieu of features shown without departing from the nature and principle of the invention.

In the drawing: Figure 1 is a longitudinal vertical section taken through the wheel box or hub and showing the wheel in elevation; Fig. 2 is a cross section on the line 2—2 of Fig. 1; Fig. 3 is a modified form; Fig. 4 is an end view of a spacing 45 ring for the rollers; and Fig. 5 is a slightly modified form of spacing ring.

A designates the body of the car, B the axle, conveniently cylindrical throughout, having the central portion B' of preferably

greater diameter than the end portion, 55 forming a shoulder as at b against which a collar b' is placed on the axle.

C designates the pedestal box having a shank portion C' through which the axle passes, the end thereof abutting the collar 60 on the axle. The outer end of the pedestal box is formed enlarged and though not necessary, the same conveniently has two diameters, the smaller or innermost diameter being designated C², and the outer C³ 65 forming a shoulder c therebetween. This said portion of the pedestal box is conveniently symmetrical on its inner face, the vertical wall c' extending to the bore thereof, while the outer flanged portion of the box 70 extends sufficiently forward or outward to constitute a housing for the inner end of the hub, presently to be described.

D designates the wheel hub, conveniently cast in a single piece having its forward end 75 closed by the integral end part D' formed with a central abutting part for the end of the axle, and an annular recess d. The diameter of the central abutting part of the end or cap portion D is slightly greater 80 than the end of the diameter of the axle, as shown in Fig. 1. The bore of the hub is conveniently uniform throughout and it has on its inner face a lining d² of the usual construction. Adjacent the inner end of the 85 hub on the periphery thereof, is an enlargement or shoulder part D³, while inwardly of the shoulder and spaced therefrom is a shoulder part D⁴, a channel d⁴ being formed between the two shoulders. The diameter 90 of the shoulders D³, D⁴ is greater than the smaller diameter of the interior of the pedestal box and slightly less than the diameter of the outer portion C³ of the pedestal box thereby forming a somewhat restricted 95 passageway between the inner walls of the pedestal box and the outer surface of the inner end of the hub part. The hub is conveniently spaced from the vertical wall c' and the shoulder part C of the pedestal box 100 by extending the axle portion until its end engages the end wall D' of the hub, thus preventing the hub from moving back on the axle to a point where the end of the hub will be in engagement with the pedestal box. 105 The collars b' (there being one on each end of the axle) serve to maintain the axle against movement and thereby the space

between the hub and the pedestal box is maintained substantially uniform during service. It may be stated that an advantage of this construction is that of avoiding wearing contact between the larger areas of the box and hub at the inner end of the latter.

Mounted within the inner end of the bore of the hub is a metallic ring E, the same being riveted conveniently and closely fitted to the inner end of the hub. This ring projects inwardly to a point in close or substantially contact relation with the axle. Projecting inwardly from the inside edge of the ring E is a lip e forming in substance an annular recess e' between the wall of the hub and the said lip, corresponding in that particular somewhat to the annular recess d at the outer end of the hub.

F designates a series of rollers arranged around the end of the axle, each being provided with central studs f at their ends. The length of the rollers is less than the distance between the projecting part of the barrier and the inwardly extending portion of the end cap, while the studs f extend outwardly from the ends of the rollers to a distance sufficient to carry the same below or beyond the projecting part e of the barrier and beyond the inwardly extending part or wall of the end cap. The studs on the rollers being located within the annular channels or spaces e' and d, serve to retain the rollers in the hub when the axle is removed.

Endwise movement of the rollers F in one direction is provided by the end thereof engaging the inner surface of the enlarged portion of the cap and movement in an opposite direction may be limited by the stud f engaging the member E or by the end of the roller engaging the part e as desired.

In some instances it may be found desirable to interpose between the thrust bearing part at the center of the end disk D' a wear plate G, the same being maintained in its position by having its edge portions dished outwardly at g in a manner to permit the studs on the ends of the rollers to occupy their proper position in the recess d. This wearing washer however may be omitted in some cases.

To retain the hub in its position against outward movement relative to the pedestal box, keys H are employed, the same passing through suitable seats or apertures in the walls of the pedestal box and through the spaces d⁴ of the hub. These keys are of a thickness less than the space d⁴, but are designed to fit against the vertical part of the flange D⁴. I have found it convenient to form these keys substantially rectangular in cross section, preferably square so that a large wearing surface will be furnished, as distinguished from the key structure shown in the aforementioned patents.

K designates a threaded plug fitted into an oil opening leading through the wall of the hub into the roller recess d.

1 represents the wheel spokes and 2 the rim.

By maintaining substantially the relative position of the hub and pedestal box as shown, whereby a tortuous space is formed between the same, it has been ascertained that the use of felt such as shown in my above mentioned patent can be avoided and in lieu thereof a heavy non-fluid grease employed. This grease can be packed into the space and will maintain its position largely by virtue of the character of the passageway or space, thus excluding all sand, grit or dust, while at the same time forming a lubricant between the parts. The grease thus indicated or referred to is shown in the drawing and it has been ascertained to be successful as a packing as well as a lubricant for this point, thus avoiding the large area contacting and wearing surface as suggested in my former patent. By forming the barrier at the inner end of the hub a thin lubricant can be employed in connection with the bearing proper and will be maintained in the wheel and in a proper position with reference to the rollers. However, in practice it is preferred to use a thick grease on the bearing as well as for the packing. This thick grease is forced into the bearing with a screw pressure grease gun. The old dirty grease is thus forced out of the wheel into the pedestal as a packing and fresh grease is put on the bearing thus automatically repacking the pedestal at each greasing of the wheel.

By this construction it will be seen that cage rings or spacing rings are avoided and that when the hub is removed the rollers will still maintain their position in the hub. It will be understood, however, in connection with the construction just described, that spacing rings without longitudinal ribs (as in ordinary roller cages) may be employed as shown in Figs. 3 and 4 of the drawing.

In the modification of the construction shown in Figs. 3 and 4, the rollers L have their ends positioned in spacing rings L', the pintles or studs at the ends of the rollers entering circular openings in the rings in a well known manner. The rollers are maintained in position in this particular form of structure by a cup shaped member M riveted to the inner end of the hub having its innermost portion bent into a point adjacent the surface of the axle. This member M takes the place of the barrier E heretofore described when referring to the other structure. In this construction the spacing rings will maintain the rollers in their proper position against falling out from the hub when the axle is removed while the

barrier prevents the removal of the rollers in an endwise direction.

In lieu of the circular perforations or bearings for the studs at the ends of the 5 rollers, as shown in Fig. 4, an oblong open ended slot 7 may be employed in the spacing rings, as shown in Fig. 5.

One of the material advantages and benefits derived from the construction and arrangement of the bearings is that when in use, the ends of the rollers or inner spacing rings are held against moving into contact with the stationary part or pedestal, differing in this particular from 15 the construction shown in the aforementioned Patent No. 907,750. Inasmuch as the pedestal box is stationary and the rollers are prevented from coming into contact therein, all wearing tendency between the 20 rollers and the pedestal is avoided.

An additional advantage may be stated to be that of preventing the rollers or their spacing rings from coming into contact with the fixed part which would tend to cause 25 improper rotation of the rollers. The construction, enables the rollers to operate at substantially the same rate of speed, and all tendency to move the rollers out of improper parallelism is largely avoided.

30 From the above it will be ascertained readily that the wheel is one embodying a minimum number of parts, can be readily assembled and one which maintains its lubricant without objectionable waste.

35 Having thus described the invention, what is claimed is:

1. In a wheel structure and in combination, a cylindrical axle part, a pedestal having a recessed outer end portion, a hub sleeved on the axle, a barrier member fixedly secured within the inner end of the hub, rollers within the hub, and means for retaining the rollers within the hub when the axle is removed.

45 2. In a car and in combination with a body, a cylindrical axle member, a pedestal member to which the axle is secured and having a recessed outer portion of different diameters forming a shouldered part between the portions, a hub loosely mounted on the end of the axle with its inner ends separated from the pedestal member by an unobstructed space, and having a projecting rib part at said inner end spaced from said 50 shouldered portion and from the pedestal box, an end thrust bearing on the hub, and means on the pedestal for securing the hub against outward movement, substantially as described.

60 3. In a wheel structure and in combination a pedestal member having a recessed outer portion of different diameters formed with a shouldered portion therebetween, a hub part having a shoulder on its periphery adjacent its inner end and fitted in said ped-

estal portion, means on the pedestal portion for maintaining the hub against outward movement, and an axle member having a cylindrical end entering the hub and secured to said pedestal portion, substantially as 70 described.

4. In a wheel structure and in combination a pedestal having a recessed outer end portion an axle, a hub sleeved on the axle and having an end positioned within a terminal recess of the pedestal, said hub also having an integral end cap portion constituting an end thrust bearing for the axle and formed with an annular recess adjacent said cap, a barrier removably secured at the 80 opposite end of the hub and having an inwardly projecting part, and a series of rollers having end studs located respectively within said recess and spaced between the inwardly projecting part of the barrier and 85 the hub.

5. In a wheel structure, the combination with a pedestal member having a recessed outer portion a cylindrical axle projecting from the pedestal, of a hub member sleeved 90 upon the axle and positioned within the recess of the pedestal, said hub member having a closed outer end formed with an annular recess on its inner wall, of a barrier member having a longitudinally projecting inner portion secured to the inner end of the hub, and anti-friction rollers in the hub having projecting portions entering between the longitudinal portion of the barrier and the hub and in the said annular recesses respectively. 95

6. In a wheel structure and in combination a pedestal box and axle secured therein, a hub member having its ends projecting into the pedestal box and formed of a single 105 casting, the end wall of which constitutes an end thrust bearing for the axle, a series of anti-friction rollers in the hub, a barrier riveted to the inner end of the hub and embracing the axle, and means for retaining 110 the anti-friction rollers in the hub, the said hub being separated from the pedestal by an unobstructed space.

7. In a wheel structure, the combination with a pedestal box, and a hub member, of 115 an axle, an end thrust bearing at the end of the hub, spaced annular flanges projecting outwardly beyond the periphery of the hub, one of said flanges substantially closing the space between the open end of the pedestal 120 box and the hub, the side walls of the other of said flanges providing an elongated vertical engaging surface, and a pin of rectangular cross section secured to the pedestal box and having a flat side arranged to engage the vertical surface of said flange, and the said pin lying within the plane of said flanges. 125

8. In a wheel structure and in combination an axle having a cylindrical part, a 130

- 4
- pedestal member having a portion to receive the end of a hub, a hub member having a closed outer end, means for maintaining the inner end of the hub in the pedestal box but out of contact therewith at all points whereby the space therebetween is unobstructed, and a lubricating packing substantially filling the space between the pedestal box and the end of the hub.
10. In a wheel construction, the combination of a pedestal member having a recess at its side, the wall of the recess being constructed to form intermediate its ends an annular shoulder, an axle projecting through the pedestal, a hub member for the axle sleeved upon the axle and having an end positioned within the recess of the pedestal, and an annular rib positioned in the space formed by said shoulder of the recess, the said hub and rib being separated from the adjacent wall of the pedestal by an unobstructed space, a lubricant packing substantially filling said space, the hub having an inward projection at its inner end separated from the vertical wall of the receiving recess of the pedestal, and a lubricant packing entirely filling the space between said inward projection of the hub and the vertical wall of the pedestal recess, said lubricant being of the pedestal recess, said lubricant being in direct contact with the hub and said pedestal.
10. In a wheel construction, the combination of a pedestal member having a recess at its side, the wall of the recess being constructed to form intermediate its ends an annular shoulder, an axle projecting through the pedestal, a hub member for the axle sleeved upon the axle and having an end positioned within the recess of the pedestal, and an annular rib positioned in the space formed by said shoulder of the recess, the said hub and rib being separated from the adjacent wall of the pedestal by an unobstructed space, a lubricant packing substantially filling said space, the hub having an inward projection at its end forming an abutment for the end of the axle, a barrier member arranged within the hub and positioned on the axle for closing the opposite end of the hub member, roller bearings interposed between the axle and the hub member, and bearings on the end projection of the hub member and said barrier member for retaining the rollers in place when the axle is removed.

In testimony whereof I affix my signature in presence of two witnesses.

ALFRED BRYANT DAY.
